UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

SEWING AND TRIMMING MACHINE.

1,082,281.

Specification of Letters Patent.

Patented Dec. 23, 1913.

Application filed July 8, 1904, Serial No. 215,796. Renewed May 19, 1913. Serial No. 768,661.

To all whom it may concern:

Be it known that I, JAMES R. MOFFATT, a citizen of the United States, residing at Chicago, in the county of Cook, State of Illinois, have invented certain new and useful Improvements in Sewing and Trimming Machines, of which the following is a description, reference being had to the accompanying drawing and to the letters and figures of reference marked thereon.

My invention relates to sewing machines, and especially to a sewing machine for use in forming hems; for the manufacture of underwear for carrying out the operation of necking undershirts, or finishing the tails of undershirts, for applique work, or for any work where one or more superposed layers of fabric are trimmed off, the raw edge thereof being sewed to the body fabric.

So far as the details of the trimming mechanism are concerned, they may be applicable to other types of machines, but the present invention has been designed especially for the necking of undershirts, where the fabric is doubled, and fed to the machine, the point of the stationary cutting member passing into the bend of the goods, the upper layer being severed and the two layers being united, the raw edge being covered by a cross thread of the stitch-forming mechanism.

In the present embodiment of the invention, the machine for carrying out said invention, comprises as to its stitch-forming mechanism, two needles set oblique to each other respecting the line of feed, a looper coöperating with each needle, whereby two lines of stitching are formed, a thread carrying finger weaving a thread back and forth between the rows of stitches, a trimmer in advance of the stitch-forming mechanism, having the stationary cutting member arranged upon the presser foot and pointed to enter between and separate the two layers of fabric, the lower one of which passes beneath the presser foot, while the upper layer is severed by the upper movable blade of the cutting member, and its raw edge is sewed down to the body fabric by the stitch-forming mechanism. One advantage of this arrangement over others for accomplishing the same work, is that the work is done right side up, in full view of

the operator, and does not have to be done on the wrong side and then turned out. 55

The invention consists in the various matters hereinafter described and referred to in the appended claims.

The invention is illustrated in the accompanying drawings, in which— 60

Figure 1 is a front view of a sewing machine, embodying my invention; Fig. 2 is a rear view; Fig. 3 is an end view; Fig. 4 is a skeletonized view of the trimmer and its operating mechanism; Fig. 5 is a sectional view illustrating the manner of adjusting the trimmer; Fig. 6 is a perspective view of a fabric sewed on my machine; Fig. 7 is an end view showing the presser foot and trimmer raised; Fig. 8 is an enlarged perspective view, illustrating the operation of sewing and trimming a fabric on this machine; and Fig. 9 is a detail view of the presser foot.

In these drawings, A represents the bed plate of a Union Special machine of a well known type.

B is the needle bar carrying the needles a, b, which are arranged in a line oblique to the line of feed. 80

Any complemental stitch-forming mechanism may be used to coöperate with the needles beneath the throat plate.

C represents the driving shaft, provided with a gear D, meshing with a gear E, upon the front face of which is an eccentric F, embraced by the lower end of an eccentric connecting rod or pitman G, which at its upper end is pivoted to the lower end of the crank arm H, attached to the rocking sleeve I on the rock shaft J, which latter is journaled in bearings on the machine frame. Said sleeve I has near its opposite end, a downwardly depending crank arm K, which is attached at its lower end to the ball stud L, which is embraced by one end of the horizontal connecting rod M, which latter at its opposite end, has a clamp embracing a ball N on the end of the stud O, which at its opposite end is fixedly sleeved upon the vertical shaft P, journaled in the head of the machine, and having means at its lower end for the attachment of the thread-carrying finger Q, which oscillates back and forth. 95

The gear E has twice the number of teeth 100 as the lower gear, hence the finger will be 105

driven to either one of its extreme positions, and dwell while the operating eccentric for the finger is passing the dead center, thus allowing the needles to stitch down to the 5 fabric the thread carried by finger Q.

The rock shaft J is journaled in bearing lugs on the rear of the machine, and is oscillated from the driving shaft through the medium of the eccentric R, the rod S and 10 the crank T secured to said rock shaft.

At its forward end, the rock shaft has secured to it a downwardly depending arm 1, provided on its lower end with a ball stud 2, which is embraced by one end of the connecting rod 3, which connecting rod at its 15 other end has a similar ball and stud connection with the arm 4, extending upwardly from the trimmer frame 5, which trimmer frame is journaled on the shaft 6, which 20 shaft is fixed to the block 7 supported from the presser bar of the machine.

The trimmer frame 5 has a forwardly extending arm 8, to which is clamped by means of the block 9 and screw 10, the upper member 11 of the trimmer. It will be seen that in the oscillation of the rock shaft J, the trimmer frame 5 will oscillate on the shaft 6, and impart vertical reciprocation to the upper trimmer blade. The lower stationary coöperating member of the trimmer is herein shown at 13, and is formed on a removable plate 14, attached to the presser foot. This lower trimming member 13, is pointed at its forward end to pierce the 30 fabric and enter between the two layers of fabric, and its pointed end forms one toe of the presser foot, the other toe 15, being upturned in the usual way.

It will be understood that the stationary 40 member 13 of the trimming device may be integral with the presser foot instead of removably attached to it.

It will be seen that as the trimmer frame 5 is journaled on a shaft 6, which is secured to a block carried by the presser bar, that the entire trimmer frame will partake of the vertical movements of the presser bar. Attached to the presser foot in rear of the forward needle is a curved guide U, 45 for deflecting the material which has been severed away from the line of stitching, leaving the raw edge of the other portion of said severed material to be covered by the cross stitch mechanism.

55 17 represents a finger extending out over the stationary member of the trimming device, which is adapted to hold the upper layer of material down upon the stationary member.

60 As a further and special improvement in a machine of this character, I have provided means whereby the trimming device may be adjusted to operate in advance of one or the other of the needles of the cross 65 stitch mechanism, thus allowing for their

right or left hand overseaming and sewing of the severed edge to the body of the goods.

The particular means for adjusting the upper blade of the trimmer is shown in Fig. 5, in which a spring surrounding the shaft and bearing at one end on the collar 18, and at the other end against the lower part of the arm extending from the trimmer frame, keeps said trimmer frame normally in a certain position; while upon the opposite side of the trimmer frame, a collar 19 is provided, which is adjusted by means of a thumb screw 20. The stationary member 13 of the cutting device, can also be adjusted laterally by means of its screw and slot engagement with the presser foot, and thus the entire trimming apparatus may be set to desired position, the spring keeping the upper trimmer member normally in operative engagement with the lower member of the trimming device.

By having the entire trimming device partake of the vertical movements of the presser bar, it will be noticed that under different thicknesses of material being sewed, the trimmer will always adjust itself to proper position, and in fact trim in different horizontal planes, in accordance with the thickness of the material being sewed.

Inasmuch as the trimming arrangement is operated from the main shaft, it will be noticed that it practically moves in unison with the movements of the needle, this being a two to one motion with respect to the 95 thread-carrying finger movement as hereinbefore described.

I have shown in Fig. 6 the work done on the machine in connection with the necking of underwear, and merely by way of 100 illustration will describe the operation of the machine in accomplishing such work, although it will be understood that the same machine may be used for hemming or finishing underwear, for applique work, or for 105 any other kind of useful or ornamental finishing of garments.

In the operation of necking underwear, the piece of goods is folded over once with the right side up, and placed in position under the presser foot. In the movement of the machine, the upper trimmer blade will come down and notch the edge of the fabric, when the pointed end of the stationary trimming member will enter between the two layers of 110 fabric.

In the further operation of the machine, the upper layer will be severed; it will be fed back to the stitch-forming mechanism; one portion of the severed fabric will be 115 deflected away by the curved guide, and the other portion will be sewed down to the body portion, and pass under the presser foot in the usual way, the raw edge being covered by the thread carried diagonally 120

back and forth by the thread-carrying finger.

Various minor modifications and changes may be made, without departing from the spirit of my invention.

Having thus described my invention, what I claim as new, and desire to secure by Letters Patent, is:—

1. In a sewing machine, the combination with a cross stitch-forming mechanism, of a trimmer arranged in advance of the stitch-forming mechanism, and in the line of the seam, said trimmer including a lower stationary member adapted to penetrate between two layers of fabric, and a movable coöperating upper member adapted to sever the upper layer of said fabric, means for feeding the fabric and means for deflecting the severed edge away from the stitch mechanism, whereby said two layers are united, and the raw edge of the upper layer covered by the cross thread of the stitch; substantially as described.

2. In a sewing machine, the combination with the presser foot thereof, of a trimmer of which the stationary member is carried by the presser foot, and is adapted to penetrate between two layers of fabric, and a movable coöperating upper member adapted to sever said fabric, and a cross stitch mechanism in rear of the trimming device, whereby said two layers are severed, and the raw edge of the upper layer covered by the cross thread of the stitch; and means carried by the presser foot for deflecting that part of the trimmed off strip which is not to be covered; means for feeding the fabrics; substantially as described.

3. In a sewing machine, the combination with cross stitch-forming mechanism, means for feeding a plurality of thicknesses of material, a trimming mechanism in advance of the cross stitch-forming mechanism and including a device for separating the thicknesses of material as the cutting is performed, said trimming mechanism including coöperating trimming blades automatically movable to allow them to cut in different horizontal planes as the thicknesses of material vary, and means for reciprocating one of said blades, the reciprocation of said blade being independent of the automatic movement; substantially as described.

4. In a sewing machine, the combination of a work support, a presser foot, cross stitch forming mechanism, means for feeding a plurality of thicknesses of material, a trimming mechanism in advance of the cross stitch forming mechanism, including co-operating trimming blades having a relative movement in a plane substantially at right angles to the work support, means for separating the thicknesses of material as the cutting is performed, means for automatically moving said trimming blades and sep-

arating means, with the presser foot of the machine, whereby the trimming blades are positioned in the plane in which they operate, so as to cut in different horizontal planes, as the thickness of the material varies, and means for giving the trimming blades a movement relative to each other.

5. In a sewing machine, the combination of cross stitch mechanism, a presser foot, a work support, means for feeding a plurality of thicknesses of material, a trimming mechanism in advance of the cross stitch mechanism, including a device for separating the thicknesses of the material, as the cutting is performed, said trimming mechanism including coöperating trimming blades having a relative movement in a plane substantially at right angles to the work support, means for operatively connecting both of said trimming blades with the presser foot, whereby said trimming blades rise and fall with the presser foot, under the action of varying thicknesses of the material and independent means for giving the trimming blades a movement relative to each other to sever the fabric.

6. In a sewing machine, the combination of stitch forming mechanism, comprising a plurality of needles, means for forming a connection between the rows of stitches, means for feeding a plurality of thicknesses of material, cutting mechanism comprising devices for cutting the upper thickness of material and separating the thicknesses as the cutting is performed, whereby only one of said thicknesses is cut, and means for guiding the free severed edge away from the needles before it reaches the same, the said needles being located behind the cutting mechanism, and operating together with the means for forming a connection between said needle stitches to secure the cut edge to the uncut fabric.

7. In a sewing machine, the combination of cross stitch-forming mechanism, means for feeding a plurality of thicknesses of material, cutting mechanism comprising a device for separating the thicknesses as the cutting is performed, whereby only one of said thicknesses is cut, and means for guiding the free severed edge away from the stitching mechanism before it reaches the same, the said stitching mechanism being located behind the cutting mechanism and arranged to sew one of the cut edges to the uncut fabric by covering the cut edge, and means to adjust said cutting mechanism across the line of the seam; substantially as described.

8. In a sewing machine, the combination of cross stitch-forming mechanism, a presser foot, means for feeding a plurality of thicknesses of material, cutting mechanism comprising a device for separating the thicknesses as the cutting is performed, whereby only one of said thicknesses is cut, and means

- carried by said presser foot for guiding the free severed edge away from the stitching mechanism before it reaches the same, the said stitching mechanism being located behind the cutting mechanism and arranged to sew one of the cut edges to the uncut fabric by covering the cut edge, means to adjust said cutting mechanism across the line of the seam.
10. 9. In a sewing machine, the combination of cross stitch-forming mechanism, including means for making two independent rows of stitching and a thread-carrying finger for depositing a thread between the two rows of stitching above the material operated upon, means for feeding a plurality of thicknesses of material, cutting mechanism comprising devices for cutting the upper thickness of material and separating the thicknesses as the cutting is performed, whereby only one of said thicknesses is cut, and means for guiding the free severed edge away from the stitching mechanism before it reaches the same, the said stitching mechanism being located behind the cutting mechanism, and arranged to sew one of the cut edges to the uncut fabric by covering the cut edge; substantially as described.
10. 10. In a sewing machine, suitable stitch-forming mechanism including a device for depositing a cross thread on the upper face of a fabric, means for feeding a plurality of layers of material, to the stitch forming mechanism, a trimming mechanism in advance of the stitch-forming mechanism and arranged to sever the top layer of fabric, means for deflecting the trimmed off portion, leaving the raw edge of the top layer to be covered by the cross thread and sewed down to the body fabric; substantially as described.
11. In a sewing machine, suitable stitch-forming mechanism including a device for depositing a cross thread on the upper face of a fabric, means for feeding a plurality of layers of material, to the stitch forming mechanism, a trimming mechanism in advance of the stitch-forming mechanism and arranged to sever the top layer of fabric, means for deflecting the trimmed off portion, leaving the raw edge of the top layer to be covered by the cross thread and sewed down to the body fabric, said trimming device being adjustable laterally; substantially as described.
12. In a sewing machine, a plurality of needles arranged oblique to the line of feed, a thread-carrying finger depositing a thread on the top surface of the material and in a line oblique to the line of feed, means for feeding a plurality of thicknesses of material, a cutting mechanism comprising a device for separating the thicknesses of material as the cutting is performed, whereby only one of said thicknesses is cut, and means for guiding the free severed edge away from the stitching mechanism before it reaches the same, the said stitching mechanism being located behind the cutting mechanism, and arranged to sew one of the cut edges to the uncut fabric by covering the cut edge with the obliquely laid cross threads; substantially as described.
13. In a sewing machine, a plurality of needles arranged oblique to the line of feed, means to operate the same vertically, a thread-carrying finger for laying a thread across the line of feed and between the needles, means to operate said thread-carrying finger, once across the line of feed to each two reciprocations of the needles into the material, a trimmer in advance of said needles and means to operate the trimmer in unison with the reciprocation of the needles; substantially as described.
14. In a sewing machine, a cross stitch mechanism including a plurality of needles arranged oblique to the line of feed, a finger for laying a thread across the line of seam, means to operate said finger, including a rock shaft and gear connection to the main shaft, whereby the finger has one reciprocation to each two of the needles, a trimmer in advance of said needles and means to operate it, including a rock shaft and eccentric connection to the main shaft for giving it reciprocation in unison with the needles; substantially as described.
15. In a sewing machine trimming device, having a movable blade, means for operating the same and a stationary blade, a presser foot carrying said stationary blade and with which the movable blade cooperates, said presser foot having also a portion of its front end upturned to allow one portion of the fabric severed to pass beneath said foot; said stationary blade having its forward end pointed to pierce the material and enter between the layers thereof, and means for feeding a plurality of layers of material to said trimmer, substantially as described.
16. A sewing machine including in combination a work support, mechanism for simultaneously stitching and covering a cut edge, a cutting mechanism located above the work support and in advance of the stitching and covering mechanism, means for feeding a plurality of layers of fabric to the cutting mechanism, said cutting mechanism including cutting devices having a relative movement in a plane substantially at right angles to the work support, and a device for lifting the upper layer of fabric from the lower layer of fabric, whereby said upper layer may be cut by said cutting devices, a device for separating the cut edges of the upper layer, whereby one of said cut edges may be separated and deflected away from the stitching and covering mechanism.

while the other cut edge of said upper layer is stitched and covered.

17. In a sewing machine, the combination of stitch forming mechanism comprising a plurality of needles and means for forming a connection between the needle stitches, feeding mechanism, and mechanism for cutting the upper thickness of material and for guiding the free severed edge away from the needles before it reaches the same, said needles being located behind the cutting mechanism, and operating together with the means for forming a connection between the needle stitches to secure the cut edge to the uncut fabric, and cover the same.

18. A sewing machine including in combination a work support, mechanism for simultaneously stitching and covering a cut edge, mechanism for supporting the upper layer of fabric above the lower layer of fabric, whereby said upper layer may be cut, and for cutting said upper layer, said mechanism including cutting devices having a relative movement in a plane substantially at right angles to the work support, said cutting devices being disposed in advance of the stitching and covering mechanism, whereby one of the cut edges of the upper layer of fabric may be stitched to the lower layer of fabric and covered.

19. In a sewing machine the combination of a work support, a presser foot, mechanism for simultaneously stitching and covering a

cut edge, means for feeding the material to the stitching mechanism, a trimming mechanism in advance of the stitching mechanism and arranged to sever the top layer of fabric, a deflecting device carried by the presser foot for deflecting the trimmed-off strip away from the stitching mechanism, and permitting the trimmed edge of the top layer to be covered by the stitching mechanism and secured to the body fabric.

20. In a sewing machine the combination of a work support, a presser foot, stitch forming mechanism, comprising a plurality of needles, and means for forming a connection between the needle stitches, feeding mechanism, mechanism for cutting the upper thickness of material, said needles being located behind the cutting mechanism, a deflecting device carried by the presser foot for engaging the trimmed off edge, and deflecting the same away from the needles, said deflecting device and sewing mechanism being so disposed that the cut edge of the upper layer of fabric will pass between the needles, whereby said cut edge is secured to the body fabric and covered by the connecting threads between the needle stitches.

In testimony whereof I affix my signature, in presence of two witnesses.

JAMES R. MOFFATT.
